L. A. WELCH.
TEMPORARY RAIL JOINT.
APPLICATION FILED FEB. 23, 1922.

1,420,070.

Patented June 20, 1922.

By Watson E. Coleman Attorney

UNITED STATES PATENT OFFICE.

LOUIS A. WELCH, OF CAMDEN, NEW JERSEY.

TEMPORARY RAIL JOINT.

1,420,070.

Specification of Letters Patent. Patented June 20, 1922.

Application filed February 23, 1922. Serial No. 538,625.

To all whom it may concern:

Be it known that I, LOUIS A. WELCH, a citizen of the United States, residing at Camden, in the county of Camden and State 5 of New Jersey, have invented certain new and useful Improvements in Temporary Rail Joints, of which the following is a specification, reference being had to the accompanying drawings.

At times rails split or break, especially when subject to intense cold and as a result of heavy traffic. If the split or break occurs between the joints of the rails, the broken adjacent ends are very liable to leave the ties, 15 or become moved laterally, causing a derailing of the train, the result of which may be more or less very dangerous.

It is, therefore, the purpose to provide a temporary rail joint to be applied to the 20 rails, not only to hold the rails in alignment, but also for preventing the rails from leaving the ties, thereby avoiding derailing of the train.

In other words the present rail joint is applied until the rails are permanently repaired, in fact until the broken rails have been replaced by new rail sections, and in this case the new rails are spiked to the ties in the usual manner, and the temporary rail 30 joints removed.

A further purpose is the provision of a temporary rail joint including a plurality of clamps applied to the opposite sides of the rails, say for instance three on each side, 35 one immediately where the break is located, and the others spaced on each side thereof a short distance from the center clamps, in combination with an elongated plate provided with operative wedge connections with 40 the clamps, to hold the clamps securely in position.

A still further purpose is the provision of a series of clamps, each embracing the base of the rail and having a portion engaged 45 with the side of the web between the base and the under portion of the ball of the rail, to reinforce the rail and hold the broken parts together and in alignment.

Additionally the invention has to do with 50 the inclined outer edges of the clamps, which incline downwardly and outwardly, in combination with notches, which are not only correspondingly formed, but are wedge shaped, so as to not only wedge in engagement with the clamps, but also to bear upon

the downwardly inclined edges of the clamps, to insure holding them down, and preventing the rail sections from leaving the ties. The clamps act to prevent lateral movement of the rails, especially since the 60 plates which have the notches are spiked to a tie.

While the design and construction at present illustrated and set forth are deemed preferable, it is obvious that as a result of a 65 reduction of the invention to a more practical form for commercial purposes, the invention may be susceptible of changes, and the right to these changes is claimed, provided they are comprehended within the scope of 70 what is claimed.

The invention comprises further features and combination of parts, as will be herein-after set forth, shown in the drawings and claimed.

In the drawings:—

Figure 1 is a view in perspective of the improved temporary rail joint constructed in accordance with the invention;

Figure 2 is a cross sectional view on line 80 2—2 of Figure 1;

Referring to the drawings, 1 designates a conventional form of tie (acting as an insert filler tie), and 2 denotes a rail, which has become broken as at 3,

In order to hold the two rail sections, which are caused to exist due to the break 3, in position, a plurality of clamps 4 is applied on each side of the rail 2. It will be noted that one clamp on each side of the 90 rail 2 is placed so that its edge where it engages the rail covers the break or joint 3 in the rail. The other two clamps of each plurality thereof, are spaced short distances from the center clamp. Each clamp comprises a body portion 5, which embraces the rail, at a point adjacent the web, overlying the base, and fitting between the base and the under surface of the ball of the rail, as at 6, 7 and 8. In fact the part of the body 100

which fits under the ball of the rail is curved to conform to the contour of the under surface of the ball, thereby not only preventing lateral movement of the rail, but also constituting a support and reinforcement for 105 the ball of the rail.

The lower part of the body 5 of each clamp, substantially midway thereof is notched and provided with a recess 9, which embraces or receives the base of the rail, 110

thereby also reinforcing the rail, as well as preventing lateral movement. In fact a portion of the clamp engages under the base of the rail, and assists materially in holding the clamp in position. As previously stated the inner base portions of the clamps 4 extend under the base of the rail, and if it were not for sinking the base portions of the clamps 4 into the filler tie, the base of the rail would 10 not engage flush with the upper surface of the filler tie. In other words the base portions of the clamps 4 are sunk into the filler tie for the purpose of permitting the base of the rail to engage flush with the tie.

15 The outer upper edge of each clamp is inclined outwardly and downwardly, and it will be noted that this inclined edge performs a very important purpose.

For instance a suitable plate 10 is provided, to rest upon the tie and is secured thereto by means of a spike 11, and is provided with a plurality of notches 12.

The bottoms 13 of these notches or recesses are inclined correspondingly to the inclination of the edges 14 of the clamps, and since the plate 10 is secured to the upper surface of the tie, the clamps 4 are held in position, and prevented from leaving the tie, thereby preventing the rail sections on each side of 30 the break 3 from leaving the ties.

It will be noted that the plate 10 is long enough, to span the distance or space between two ties, (not shown) so that this plate may rest upon two adjacent ties, and 35 by inserting a filler tie (shown in Figure 1) between the two ties where the joint 3 may be caused to be formed in the rail, the plate 10 may be fastened to the filler tie. In other words supposing the rail, due to intense cold, 40 should become broken at a point between two adjacent ties, an insert tie may be applied, and then the plate 10 may be fastened thereto, and hence prevent lateral movement of the broken adjacent ends of a rail section.

45 The notches or recesses 12 also have upwardly converging side walls. In fact the notches or recesses 12 are more or less wedge shaped, so that the side walls of the notches or recesses may wedge in engagement with 50 the opposite faces of the clamps 4, and thereby assist in preventing outward movements of the rails.

The notches or recesses 9 embrace the base of the rail sufficiently to hold the rail sections in position, and allow them to expand

and contract incident to the change in temperature.

The invention having been set forth, what is claimed is:—

1. The combination with the broken ends 60 of rail sections, of a plurality of clamps on each side of the rail sections, embracing the base thereof and fitting between the base and the ball of the rail, an elongated holding plate spiked to the tie and having means in wedging engagement with the clamps to hold them against the rail sections and to prevent them from leaving the tie.

2. The combination with the broken ends 70 of rail sections, of a plurality of clamps embracing the base of the rail and fitting between the base and ball of the rail, a plate secured to the tie and having means wedgingly fitting the clamps for holding them down and in embracing engagement with 75 the rail sections.

3. The combination with the broken ends 80 of rail sections, of a plurality of clamps embracing the base of the rail and engaging between the base and the ball of the rail, a plate secured to the tie and provided with a plurality of notches having a wedging engagement with the clamps to hold them in position and against the rail sections.

4. The combination with the broken ends 85 of rail sections, of a plurality of clamps on each side of the rail sections, each embracing the base of the rail and engaging between the base and the ball of the rail, a plate secured to a tie and having notches, which are 90 tapered or wedge shaped, so as to wedge in engagement with the clamps to hold the clamps in position.

5. The combination with the broken ends 95 of rail sections, of a plurality of clamps on each side of the rail sections, each embracing the base of the rail and engaging between the base and the ball of the rail, a plate secured to a tie and having notches, which are 100 tapered or wedge shaped, so as to wedge in engagement with the clamps to hold the clamps in position, the outer edges of the clamps inclining downwardly and outwardly, the bottoms of the notches or recesses incline downwardly and outwardly, and overlying the edges of the clamps, to hold the clamps down and in position.

In testimony whereof I hereunto affix my signature.

LOUIS A. WELCH.
